(57) **CLAIM**

The ornamental design for a motorbike seat with battery box, as shown and described.

DESCRIPTION

FIG. 1 is a top, front, and left side perspective view of a motorbike seat with battery box embodying our new design as installed on an exemplary motorbike;

FIG. 2 is a top, rear, and right side perspective view thereof;

FIG. 3 is a top, front, and left side perspective view thereof;

FIG. 4 is a top, rear, and right side perspective view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a top plan view thereof; and,

FIG. 10 is a bottom plan view thereof.

The broken line showing of portions of the motorbike are provided for the purpose of illustrating environmental structure and form no part of the claimed design.

1 Claim, 6 Drawing Sheets
